UNITED STATES PATENT OFFICE.

CHARLES EDWARD HAVILAND, OF LIMOGES, FRANCE.

DESIGN FOR A PLATE.

SPECIFICATION forming part of Design No. 22,617, dated July 18, 1893.

Application filed June 22, 1893. Serial No. 478,510. Term of patent 14 years.

To all whom it may concern:

Be it known that I, CHARLES EDWARD HAVILAND, a citizen of the United States, residing at the city of Limoges, in the Republic of France, have invented and produced a new and original Design for a Plate and other Articles, of which the following is a specification, reference being had to the accompanying drawings forming part thereof, and in which—

Figure 1 is a top view of a plate bearing my design, and Fig. 2 is a detached sectional view of same on the dotted line 2—2 of Fig. 1.

The leading feature of my design consists of the edge ornamentation along the rim of the plate or other article, substantially as shown in the accompanying drawings.

In the drawings A designates the rim of the

plate, and B the ornamentation along the edge thereof, the said ornamentation consisting of the scalloped heading *a* curved inward at intervals, as shown at *b*, and the ornate surfaces *c* filling out the spaces outlined by said inward curves *b* and continuing the edge line of the rim.

What I claim is—

The design for a plate and other articles, substantially as shown and described.

Signed at the city of New York, in the county and State of New York, this 20th day of June, 1893.

CHARLES EDWARD HAVILAND.

Witnesses:

EDWIN HAVILAND,
CHAS. C. GILL.
